CASTING METHOD

Raymond D. Zinn, San Jose, Calif., assignor to United Aircraft Corporation, a corporation of Delaware
Filed July 14, 1961, Ser. No. 124,116
3 Claims. (Cl. 264—225)

This invention relates to a novel casting technique and more particularly relates to a core structure whereby castings with complicated coring can be made with cores which are easily removable from the casting after the latter has hardened. The invention is particularly applicable to the casting of propellants in solid propellant rocket engines and will be described in terms of casting such propellants. However, it will be apparent from the specification which follows that the invention is one of broad applicability and can be used in making castings of various materials.

In making castings, such as in a solid propellant rocket motor, it is frequently desirable to provide a core of some complex shape which can be removed through a small opening after the casting is completed. In the past, cores have been made of various materials such as wax, sand, salt, plaster or the like which can be removed by heating, shaking, chipping, washing or the like. Cores have also been used wherein the core is made of a plurality of keyed segments of a solid material which can be removed in pieces. Such methods have not been fully satisfactory from several standpoints. For one thing, in the removal of such cores, there is always the possibility of damaging the casting since many castings are made of materials which can be easily damaged. Another disadvantage is that the castings are frequently made of a highly combustible material and there is always the possibility of fire or explosion when heat or mechanical force is applied to the casting to remove the core. Further, many of the prior art methods do not leave a completely smooth inner surface but the surface frequently has small ridges or other irregularities therein. The core material of many prior art methods contaminates the propellant grain, causing ignition difficulties.

In accordance with the present invention, a method and apparatus are provided for the manufacture of castings wherein the core comprises a flexible member which is made temporarily rigid by filling it with a soluble or meltable filler compound so that the rigidized core is held to a desired shape during casting but can be collapsed and removed through a small opening after the casting has hardened.

A primary object of this invention is to provide a casting method wherein a core is provided which can be easily removed after the casting is completed.

Another object of the present invention is to provide a casting method which has a high safety factor in core removal.

Still another object of this invention is to provide a casting method wherein a core is used which leaves a completely smooth surface on the casting.

Still another object of this invention is to provide an economical core which does not utilize expensive materials and which can be fabricated and used with a minimum of labor.

A still further object of this invention is to provide a core structure which does not contaminate the propellant surface.

Another object of this invention is to provide a core structure which can be installed and withdrawn through an opening smaller than the core.

Other objects and features of advantage of the present invention will be apparent from the specification which follows.

In the drawings forming part of this application:

2

FIGURE 1 is a perspective view of a rigidized core showing the mold in which the core is made.

FIGURE 2 is an enlarged sectional view of a core made in accordance with the present invention.

5 FIGURE 3 is a sectional view showing the method of making a casting employing the present invention.

FIGURE 4 is a sectional view similar to FIGURE 3 showing one method of de-rigidizing the core.

10 FIGURE 5 is a similar sectional view showing the removal of the flexible member from the otherwise finished casting.

FIGURE 6 is a sectional view showing a casting which has been manufactured in accordance with the present invention.

FIGURE 7 is a sectional view showing the method of utilizing the core of the present invention wherein the core is withdrawn through a small opening in a motor.

20 FIGURE 8 is a view similar to FIGURE 7 showing a completed rocket motor made in accordance with the present invention.

Referring now to the drawings by reference characters, there is shown in FIGURE 1 a mold 7 made of segments 8 and 10 which mold is used for making the core of the present invention. In the present illustration the core is 25 relatively simple and the mold merely has a first cylindrical section 12 and a second cylindrical section 14 connected by a disc-like section 16. It will be understood, of course, that the simple symmetrical shape shown is only for purposes of illustration and that the mold for the core can be made in substantially any desired shape. The mold 7 can be made of any suitable material such as metal, wood, plastic, ceramic, plaster or the like. In making the core, a flexible member 18 is provided which generally conforms to the desired shape of the finished core or which 30 can be stretched to the desired shape. The member 18 can be of any flexible material which is inert to the material being cast, which has sufficient flexibility to conform to the desired shape and sufficient mechanical and thermal stability to stand the ultimate casting and/or curing operation. Preferably the flexible member is a rubber impregnated cloth preformed to the desired shape. The rubber impregnated cloth forms an excellent release agent for castable solid propellants. The member 18 is placed 35 in the core mold 7 and the mold sections are closed around the member 18. A mandrel 20 is then placed through the core and a filler compound 22 is then run into the flexible member 18, preferably under pressure so that the member 18 is made to conform to the inner configuration of the mold. The filler material 22 can be any desired 40 soluble or meltable material but is preferably a water soluble plaster. Although the flexible member 18 can be rigidized by filling it in its entirety with the filler compound in some instances, portions of the rigid filler can be precast. Thus, to make the core shown in FIGURE 2,

45 one might first place a cylindrical pre-cast filler element 22a on the mandrel 20, enclose the same in the mold and then cast in place the center disc-like section 22b. A third pre-cast cylindrical section 22c can then be inserted to complete the core.

50 After the core has been completed, the core, now generally designated 24, is placed in a mold 26 and the casting compound 28 poured through the opening 30. In the instance illustrated, the casting compound 28 might well be a rubber-like material with an oxidizer salt therein, as is well known in the solid propellant art. After the mold is 55 filled, it is heated to polymerize the propellant, whereupon it will form the solid polymerized material 32. At this point, the mandrel 20 is withdrawn leaving a central opening through which water can be passed as at 34. This 60 dissolves out the filler compound leaving only the flexible member 18 in place. Although for purposes of illustration water has been shown as being passed through the center,

an organic solvent might be used in the case of some 5 filler materials or in the case of other filler materials the filler might be merely heated and allowed to drip out. If only one end of the core is accessible, the solvent must be introduced and withdrawn from the same end. After substantially all of the filler material has been withdrawn as is shown in FIGURE 4, the flexible member 18 can now be withdrawn from the casting as is shown in FIGURE 5. The mold 26 is then disassembled leaving the casting with its irregular opening 38 as is shown in FIGURE 6. 10

In FIGURES 7 and 8 the invention is illustrated in connection with a rocket motor leaving an opening smaller than the desired core. Here a single piece case generally designated 40 is made of fiberglass 42. The core includes a small neck portion 44 which is smaller than the 15 desired core. Here the rubber impregnated cloth mandrel 46 is inserted through the neck opening 44 and filled with a water soluble plaster 48. The propellant 50 is then poured in place and cured. The plaster 48 is then dissolved out and the cloth 46 can then be pulled out. This 20 leaves the completed motor shown in FIGURE 8. The cavity 52 is obviously larger than the neck opening 44.

It is believed apparent from the foregoing that I have provided a superior method of making a casting with an irregular opening therein.

I claim:

1. A method of making a casting having a hollow portion therein comprising:

(a) placing in a die a continuous open-ended webbing member capable of being filled to form a solid, open-ended body, said webbing member having sufficient flexibility to conform to the desired shape of a hollow portion of said die, said die having a passage extending through at least one end thereof to said hollow portion;

30
35

- (b) inserting a mandrel through said passage into said webbing material in said hollow portion whereby to envelope the sides of said mandrel with said webbing material;
  - (c) injecting into the space between said mandrel and the adjacent webbing a flowable filler material capable of being treated to form a rigid, soluble filler, the position of said mandrel being adjusted such that after said filler is injected the ends of said mandrel remain uncovered;
  - (d) treating said filler material to cause it to harden to form a rigid core;
  - (e) molding casting material about said core while maintaining the ends of said mandrel in an exposed condition and withdrawing said mandrel to provide a passage entirely through said core;
  - (f) flowing a solvent for said filler material through the passage so formed whereby to dissolve and remove said filler;
  - (g) and removing the said flexible webbing from the casting so formed.
2. The method of claim 1 wherein the filler material is water-soluble plaster.
3. The method of claim 1 wherein the webbing member is a rubber-impregnated cloth.
